UNITED STATES PATENT OFFICE.

JACOB MEYERHOFF, OF CHICAGO, ILLINOIS.

SHIRT.

1,284,126.

Specification of Letters Patent.

Patented Nov. 5, 1918.

Application filed August 28, 1916. Serial No. 117,290.

To all whom it may concern:

Be it known that I, JACOB MEYERHOFF, a citizen of the United States, and a resident of the city of Chicago, county of Cook, and 5 State of Illinois, have invented certain new and useful Improvements in Shirts, of which the following is a specification.

My invention relates to improvements in shirts designed for use especially by men, 10 and has for its object the production of a shirt which will be so constructed as to be adapted, when worn, to be securely fastened at its lower end so as to prevent the same from moving upwardly out of the trousers 15 of the wearer.

A further object is the production of a garment, as mentioned, which will be of extremely simple construction, one which may be readily and easily applied and the 20 lower end thereof fastened to the wearer, and which will be comfortable in wear.

Other objects will appear hereinafter.

With these objects in view, the invention consists in the combinations and arrangements 25 of parts hereinafter described and claimed.

The invention will be best understood by reference to the accompanying drawings forming a part of this specification, and in 30 which,

Figure 1 is a perspective view illustrating the manner of arrangement of the shirt when worn, and

Fig. 2 is a front view of the shirt, removed.

The preferred form of construction, as illustrated in the drawings, comprises a shirt 1 having a divided front, forming flaps 2 and 3. Said flaps 2 and 3 are provided, at 40 their lower or adjacent corners, with button holes 4 and 5. At the back of the shirt, adjacent the lower end thereof, are provided two considerably spaced buttons 6 and 7.

In using the shirt, the flaps 2 and 3 are 45 passed rearwardly between the legs of the wearer and crossed, the flap 2 being buttoned to the button 7, whereas the flap 3 is secured to the button 6, said buttons 6 and 7 thus engaging with the button holes 5 and 4 50 respectively.

With this arrangement, it will be seen

that the lower end of the shirt will be securely drawn about the hips of the wearer, as clearly shown in Fig. 2, so as to prevent the same slipping upwardly. At the same 55 time, the waist of the wearer will be loose and free, the same being permitted to assume its natural position.

Applicant is aware of the fact that shirts have heretofore been provided wherein an 60 extension is provided at the back or front of the shirt which is passed between the legs of the wearer and secured at the opposite side of the shirt, but this arrangement has proven unsatisfactory and ineffective 65 for the reason that with this arrangement the sides of the lower end of the shirt are left unfastened, and consequently draw upwardly and in time protrude from the trousers. With applicant's construction, how- 70 ever, the sides of the lower end of the shirt are drawn snugly about the body of the wearer and are thus as securely locked against upwardly slipping as the central 75 portions of the shirt. The buttons 6 and 7 are arranged well to the sides of the back 75 of the shirt, as seen, so as to aid in the securing of the side portions of the shirt, as just mentioned, this position of the buttons, also bringing the same to positions where 80 the same offer the least discomforture to the wearer of the garment. Moreover, said buttons, in these positions, are very readily accessible so as to permit of ready buttoning or unbuttoning of the flaps of the shirt. 85

While I have illustrated and described the preferred form of construction for carrying my invention into effect, this is capable of variation and modification without departing from the spirit of the invention. I, 90 therefore, do not wish to be limited to the precise details of construction set forth, but desire to avail myself of such variations and modifications as come within the scope of the appended claim. 95

Having described my invention what I claim as new and desire to secure by Letters Patent is:

A shirt having a divided lower front portion forming right and left hand front flaps, 100 each of said flaps being passed diagonally rearwardly between the legs of the wearer,

the left hand flap passing to the right side of the back of the shirt and the right hand flap passing to the left side of the back of the shirt, said flaps crossing each other between the legs of the wearer; and means for fastening said flaps in said positions, substantially as described.

In testimony whereof I have signed my name to this specification in the presence of two subscribing witnesses.

JACOB MEYERHOFF.
